UNITED STATES PATENT OFFICE.

ARMAND MÜLLER-JACOBS, OF NEW YORK, N. Y., ASSIGNOR TO CATHERINE MÜLLER-JACOBS, OF BROOKLYN, NEW YORK, AND EDWARD WEINGARTNER, OF NEW YORK, N. Y.

EXPLOSIVE AND PROCESS OF MAKING SAME.

SPECIFICATION forming part of Letters Patent No. 777,125, dated December 13, 1904.

Application filed June 13, 1902. Serial No. 111,543. (No specimens.)

To all whom it may concern:

Be it known that I, ARMAND MÜLLER-JACOBS, a citizen of the United States, residing at New York, in the county of New York and State of New York, have invented certain new and useful Improvements in the Manufacture of Explosives; and I do hereby declare the following to be a full, clear, and exact description of the invention, such as will enable others skilled in the art to which it appertains to make and use the same.

My invention relates to an improved explosive and a method of producing the same.

My object is to produce by methods which will greatly minimize the dangers incident to manufacture and use explosives that shall be easy of manipulation, safe in handling, adapted to use in a variety of connections, and in which the elements shall be so closely and intimately associated as to produce practically perfect and instantaneous combination and consequent enhancement of potential energy—i. e., development of the gaseous products of the composition.

In the production of the explosive by my improved method I utilize to a large extent apparatus such as is ordinarily used in the dyeing, sizing, and printing of textile fabrics and warps and in the coating or grounding and printing of wall-paper and other paper, thus contributing to cheapness of manufacture, or my method may be carried out with some degree of success by hand.

While my invention resides in the novel method or process independent of any particular kind of machinery or apparatus that may be used, yet I have in the accompanying drawings illustrated a type of apparatus that may be employed.

In the drawings, Figure 1 is a central vertical longitudinal section through tanks containing a bath of nitric and sulfuric acids and also showing in central vertical transverse section rollers used in connection with the tanks.

Fig. 2 is a central vertical transverse section of the drying cylinders or rollers. Fig. 3 is a view similar to Fig. 1 of a tank containing a bath of caustic alkali or the like and of rollers used

in connection therewith. Fig. 4 is a view similar to Fig. 1 of a tank containing a bath of fresh water and of rollers used in connection therewith. Fig. 5 is a view similar to Fig. 1 of the drying-room and of the rollers used in connection therewith, and Fig. 6 is a view similar to Fig. 1 of tanks containing suitable chemicals for increasing or decreasing the explosive energy of impregnated material passed therethrough and of rollers used in connection therewith.

Referring to the drawings in detail, in carrying out my improved process I take ordinary cotton cloth, boiled, bleached, and dried, wind the same on a roller, and thence pass it by hand or machinery such as is ordinarily used for mordanting, dyeing, and padding or sizing processes in the textile industry, preferably over a roller or rollers *a*, through a mixture of concentrated nitric and sulfuric acid in about the proportion of one part of nitric to three parts of sulfuric, the same being contained in an appropriate stone or glass vessel or vessels *A*. In its course through said vessels the cloth is also passed over a roller or rollers *a*. The cloth being thus treated is also passed between two or more heavy rollers *a'*, preferably, of glass or porcelain, by which the surplus acid is pressed out and allowed to flow back into the vessel, where it may be again used. The cloth is then wound upon another cylinder or roller or upon cylinders or rollers *B* and allowed to stand for from one to three hours, after which it is passed through a bath of dilute caustic alkali or a carbonate of an alkali or an alkaline earth, care being taken that this latter bath never becomes acid. This alkaline bath is contained in an appropriate vessel, tank, or vat *C*, containing any number of rollers *c*, over which the cloth passes in its course through the vessel *C*. The cloth is then thoroughly washed in a continuous stream of fresh water contained in a vessel or tank *D*, containing rollers *d*, over which the cloth passes in its course through the tank *D*, and afterward dried over rollers *e* in a "hot flue" or room *E* at a temperature not exceeding 100° to 105° Fahrenheit.

heit, the currents of hot air entering the room E through pipe e' , and thence through apertures e^2 in a partition e^3 to the cloth on the rollers e , (the apertured partition thus acting evenly to divide the currents of hot air over the different rollers,) and thence through shuttered openings e^3 in the ceiling or roof of the room. The cloth enters the room at the aperture e^4 between rollers e^5 , and after leaving the room E is then wound again upon a suitable cylinder or roller. (Not shown.) This cloth now constitutes without further treatment a powerful explosive, somewhat similar in its properties to guncotton, though more stable and uniform in its effects. I may proceed further, however, to increase or reduce its explosive energy or retard or accelerate its action by applying to one or both sides of the warp or cloth, as by printing, certain other chemicals adapted to obtain the object desired, these chemicals being mixed with a suitable adhesive and placed in a vessel or vessels F and applied in much the same way as ordinary colors are applied to textile fabrics. In preparing such chemicals for surface printing I may, for instance, dissolve picrate of potassium or ammonium in water or dissolve soluble chromates, bichromates, chlorates, nitrates, organic azo-diazo, nitroso, or nitro compounds in appropriate quantities, alone or together and mixed with a suitable thickening material—as, for example, gum arabic, tragacanth, starch or its derivatives, glue, gelatin, albumen, casein, or the like. I may also use nitroglycerin, nitrostarch, nitromannite, or the like in printing, or I may print with mixtures appropriately thickened, as aforesaid, containing finely-divided amorphous substances, such as sulfur and carbon, in the form of lampblack, or solid hydrocarbons, with or without insoluble chromates, fulminates, or the like, there being no danger of explosion during the process of manufacture so long as the materials operated upon are moist and the temperature kept sufficiently low, in most cases not to exceed 100° to 105° Fahrenheit. By thus printing upon the nitrated cotton with certain of the various chemicals referred to I am able to produce an explosive of any desired intensity or rapidity. These chemicals are contained in the vessels F, as stated, in which revolve rollers f. Located above and in juxtaposition but revolving in the opposite direction to said rollers are larger rollers f', these latter rollers being located radially about a large roller f'', and between these rollers f' and this roller f'' the cloth passes, being fed therebetween over small guiding-rollers f³, the cloth finally passing over the guiding-roller f⁴.

If desired, for certain purposes instead of using the cotton fabric nitrated, as above set out, I may print with the chemicals stated upon any other kind of textile fabric in its natural state—such as cotton, silk, artificial silk, mo-

hair, woolen or linen goods; also, on yarns and warps made of the aforesaid and similar materials; also, on felt, paper, or sheets of asbestos or any other suitable material.

As an instance of one formula by which the printing mixture may be compounded may be cited ten parts picrate of ammonia, five parts chlorate of potassium, dissolved in eighty parts of water and thoroughly mixed with twenty parts of concentrated mucilage of gum-tragacanth, or I may use thirty parts of talcum or china-clay in sixty parts of water, adding fifteen parts of nitroglycerin with twenty parts of concentrated water solution of gum-arabic. After printing the fabric or warp in the manner usually employed in printing with colors in the textile industry the product is dried in the usual manner, care being taken that the temperature shall not exceed 100° to 105° Fahrenheit. The product is then preferably cut into narrow ribbon-like strips to accord with the width or size of the caps, cartridges, shells, or bombs which are to be filled therewith, the prepared strips being tightly rolled by hand or machinery, when they are ready to be inserted. Warps or yarns thus impregnated and rendered explosive may be also wound upon hollow frames or cylinders of explosive composition or easily-inflammable material, such as celluloid or other suitable substance, the interior being adapted to be filled with any appropriate supplementary explosive. The product thus made can be readily exploded in the ordinary way, as by detonation, friction, concussion, or the like.

It will be seen that by my improved method as above set out I am able to produce an explosive adapted to the varying needs of different conditions of use and which is readily handled for transportation and distribution; also, that by my method I do away to the greatest possible extent with the dangers which are usually incident to the manufacture of high explosives and at the same time bring about a most perfect and intimate association of the chemical constituents of the explosive.

Having thus fully described my invention, what I claim as new, and desire to secure by Letters Patent, is—

1. The method of manufacturing explosives, which consists in printing upon the surface of a nitrocellulose with a solution of picrate of ammonia and chlorate of potassium, substantially as described.

2. The method of manufacturing explosives, which consists in printing upon the surface of a nitrocellulose with a solution of picrate of ammonia, chlorate of potassium, and a suitable adhesive, substantially as described.

3. The method of manufacturing explosives, which consists in printing upon the surface of a nitrocellulose with a solution of picrate of ammonia, chlorate of potassium, and gum-tragacanth, substantially as described.

4. The method of manufacturing explosives,

- which consists in printing upon the surface of a nitrocellulose with a water solution of picrate of ammonia and chlorate of potassium, substantially as described.
5. The method of manufacturing explosives, which consists in printing upon the surface of a nitrocellulose with a water solution of picrate of ammonia and chlorate of potassium, with a suitable adhesive, substantially as described.
10. 6. The method of manufacturing explosives, which consists in printing upon the surface of an explosive cellulose compound with a solution of picrate of ammonia, chlorate of potassium, and gum-tragacanth, substantially as described.
15. 7. The method of manufacturing explosives, which consists in printing upon the surface of a cellulose, that has been treated to suitable acids and alkalies, with a water solution of picrate of ammonia, chlorate of potassium, and gum-tragacanth, substantially as described.
20. 8. As a composition of matter, an explosive cellulose compound having applied to the surface thereof a mixture of picrate of ammonia and chlorate of potassium, substantially as described. 25
9. As a composition of matter, an explosive cellulose compound having applied to the surface thereof a mixture of picrate of ammonia, chlorate of potassium, and an adhesive, substantially as described. 30
10. As a composition of matter, an explosive cellulose compound having applied to the surface thereof a mixture of picrate of ammonia, chlorate of potassium and gum-tragacanth, 35 substantially as described.

In testimony whereof I affix my signature in the presence of two subscribing witnesses.

ARMAND MÜLLER-JACOBS.
